HAIRPIN

Frank Beiter, New York, N. Y.

Application January 20, 1938, Serial No. 185,835

4 Claims. (Cl. 132—50)

This invention relates to hair pins in general and particularly to what may be termed safety hair pins.

One of the objects of my invention is to provide simple, inexpensive hair pins which will have the tendency of clamping a substantial portion of the hair engaged by the pin in a substantially flat fashion, and in a direction substantially adjacent to the head, whereby the hair pin is not only prevented from becoming loose, but whereby the pin is forced into a flat position relative to the head.

Another object of this invention is to provide a hair pin made of a wire structure, preferably of round or circular cross section, and which structure consists of four distinct parts i. e. a highly resilient, relatively short or small loop at one end of the structure, two parallel pairs of leg portions, of which in one pair the legs are adjacent to each other, whereas in the other pair the leg portions are spaced from one another, and finally an angular connection between the two parallel leg portions, which connection is very gradually tapered so as to ease the hair to be held by the pin gradually into a flat position and without bunching it.

Another object of this invention is to so dimension the two parallel leg portions that they substantially equal in length, for the purpose of accommodating approximately equal parts of hair, so that the twisting motion exerted by one part of the hair, held between one pair of the leg portions, will be counteracted by the hair held between the other parallel leg portions, thereby assuring the pin's laying substantially flat against the head.

Another important object of this invention is to bodily curve the wire structure of the pin so as to approximate the curvature of the head.

The foregoing and still further important objects and advantages of my invention will become more fully apparent from the ensuing description and the accompanying drawing, which latter, although illustrating specific forms, is by no means intended to limit me to the actual showing, and in which

Fig. 1 illustrates one of my pin constructions.

Fig. 2 illustrates another form of my pin construction.

Fig. 3 is a side elevation of Fig. 2.

Figs. 4 and 5 illustrate modified forms of my pin construction.

Fig. 6 is a plan view, and Fig. 7 is a side view of another embodiment of my pin construction with flattened adjacent parallel leg portions, and

Fig. 8 is a modified form of Fig. 6.

Referring now specifically to the drawing, from Fig. 1 it will be clearly seen that the structure of my hair pin consists of the relatively small and narrow resilient loop 10, from which extend, in closely adjacent parallel relation, leg portions 11 and 11', which are extended into spaced parallel leg portions 12 and 12' by way of gradually diverging connections 13.

The hair engaged by the pin is indicated by 10 parallel lines.

It will be seen that the adjacent leg portions of the pin engage the hair so that hair portion H passes over leg portion 11, and under leg portion 11' up to about the middle of diverging leg connection 13, whereas the other, directly opposite half of the hair portions H', passes under adjacent leg portion 11'. Engaged by leg portions 12 and 12', the hair strands pass in opposite direction, that is to say, hair portion H1 passes under leg portion 12, while hair portion H2 passes over leg portion 12'. In this way the twisting motion imparted to the pin by hair portion H in downward direction, will be counteracted by hair portion H1 tending to twist the pin in upward direction. The same applies to hair portions H' and H', since hair portion H' tends to lift leg portion 11', whereas hair portion H2 tends to bear down against leg portion 12'. These oppositely acting forces result in the pin remaining flat against the head.

In inserting the pin into the hair, it is advantageous to first run either of the spaced leg portions (12 or 12') under the hair, while lifting the other leg portion above the hair, and when sufficient hair is passed in between leg portions 11 and 11', the position of leg (12 or 12') is reversed, whereby the hair is held in the manner shown in Fig. 1.

In order to accommodate the hair pin more readily in respect to the head, the pin structure is preferably curved, as indicated in Figs. 3 and 7, which curvature approximates that of the head.

It is to be observed that the distance between the two spaced leg portions 12 and 12' approximately equals the width or breadth of loop 10.

In Figs. 2 and 3 is shown a similar structure to that illustrated in Fig. 1, wherein the two adjacent parallel leg portions 14 and 14' are superimposed above one another, and loop 10' is twisted at 15. A similar twist of the wire structure will be seen at 16, where leg portions 14 and 14' commence to diverge. The operation of this device is very similar to that explained in connection with Fig. 1.

In Figs. 4 and 5 I have illustrated still another modified form of my hair pin where the adjacent parallel leg portions 17 and 17' and 18 and 18', respectively, are in a horizontal plane next to one another and in substantially the same plane as spaced leg portions 19 and 19' and 20 and 20', respectively. The wire parts between the loops and the adjacent leg portions, and between the adjacent leg portions and the diverging connections 21 and 21' and 22 and 22', respectively, are crossed, as indicated at 22, 23, 24 and 25.

In Fig. 4 adjacent leg portion 17' passes over the leg portion 17, whereas in Fig. 5 the left-hand adjacent leg portion 18 passes over right-hand leg portion 18'. I prefer constructing the modified forms shown in Figs. 4 and 5 in the way illustrated in Fig. 5 for right-handed persons, whereas the arrangement shown in Fig. 4 is intended for left-handed persons.

Referring now to Figs. 6, 7 and 8, in these figures are illustrated hair pins similar to those shown in Figs. 4 and 5, with the variation that the adjacent leg portions 26 and 27, 28 and 29 are flattened for the purpose of accentuating the holding of the air in flat position by and between these leg portions. In comparing Fig. 6 with Fig. 8, it will be again seen that in Fig. 6 the portion 27 overlaps portion 26, whereas in Fig. 8 the portion 29 overlaps portion 28.

The loops in all of the structures shown are relatively small and narrow; as material for the hair pin I prefer employing round stock, which I first anneal, bend, twist and flatten as the case may be, whereupon I harden the material by wellknown processes so that the loop becomes highly resilient and prevents the pin from changing its intended shape. From Figs. 3 and 7 it will be clearly seen that I also prefer to curve my hair pin for accommodating the curvature of the head.

While I have illustrated and described specific forms of my invention, it is quite obvious that slight improvements in shape and arrangement may be made to increase the efficiency or enhance the appearance of my device, and especially where hair pins may be required for particular purposes, such as elaborate hair dressing, as long as the principle of my hair pin, of holding the hair flat, and being held flat against the head, is adhered to, and I therefore preserve for myself the right to make such changes and improvements in my invention, without departing from its broad scope, as expressed in the annexed claims.

I claim:

1. In a hair pin, a wire structure comprising a relatively short, small, resilient loop, a pair of closely adjacent, superimposed parallel leg portions extending from the loop and intended for holding flatly a portion of hair engaged by the pin, another pair of parallel, but spaced leg portions forming continuations of the superimposed leg portions; angular, very gradually inclined connections joining the two pairs of leg portions, the distance between the spaced leg portions substantially corresponding to the width or breadth of said loop, said superimposed and said spaced parallel leg portions being substantially of equal length.

2. In a hair pin, as set forth in claim 1, said closely adjacent, superimposed leg portions overlapping one another.

3. In a hair pin, as set forth in claim 1, and wherein the wire material of the pin is of originally circular cross section, said closely adjacent, superimposed leg portions being flattened and overlap one another.

4. In a hair pin, as set forth in claim 1, and wherein the body of the structure is curved to approximate the curvature of the head.

FRANK BEITER. 40
